UNITED STATES PATENT OFFICE.

ALBERT J. HOLT, OF MUSKOGEE, OKLAHOMA.

RAILWAY-RAIL JOINT.

986,005.

Specification of Letters Patent. Patented Mar. 7, 1911.

Application filed January 5, 1909. Serial No. 470,790.

To all whom it may concern:

Be it known that I, ALBERT J. HOLT, a citizen of the United States, residing at Muskogee, in the county of Muskogee and State of Oklahoma, have invented certain new and useful Improvements in Railway-Rail Joints, of which the following is a specification.

This invention relates to improvements in railway rail joints, but more particularly to the ends of the rails, which are inclined or tapering transversely in a vertical direction, the inclined portion thereof beginning a sufficient distance from the edge of the rail and extending across the face thereof to warrant strength and durability of the parts.

This invention further relates to the shoulder formed at the beginning of the inclined portion thereof and also the right angled portion at the termination of each incline which abuts against the shoulder in the adjacent rail. By this means the incline cannot slip through expansion of the rails, as the abutting portions form abrupt stops similar to a square rail joint.

This invention further relates to the lugs integral with the inclined lateral surface thereon, and also relates to the recesses in the rails for said lugs to enter. The lugs and recesses are on each opposing inclined lateral face. By this construction the rail joints are prevented from any independent vertical movement, or displacement, when secured between fish plates.

The object of the present invention is to provide a rail joint that will be durable in its construction, symmetrical in its contour, and resist any strain that may come upon the joints from rough traffic on a railway, but more especially on a curve where the greatest strains occur. With the old right-angled abutting joint at present used on railways, there is no provision for lateral strains as the abutting joints rely solely upon the fish plates to hold them in position.

With applicant's incline overlapping rail joints, there is no possibility for the least lateral strain to manifest, as one incline bears against its opposing incline. By this construction of overlapping joints considerably less strain bears upon the fish plates.

With the foregoing and other objects in

view, the invention consists in the details of construction and in the arrangement and combination of parts to be hereinafter more fully set forth and claimed.

In describing the invention in detail, reference will be had to the accompanying drawings, forming part of this specification, wherein like characters denote corresponding parts in the several views, in which:

Figure 1 represents the improved rail joint in perspective view. Fig. 2 represents in plan view and partly in section the device which is partly broken away. Fig. 3 represents a portion of a rail in horizontal section. Fig. 4 represents in perspective view a portion of a rail indicating a lug and a recess thereon. Fig. 5 represents the device in an end view secured to a fish plate.

The principal feature of this invention consists in the construction of the rail joints, the rail A having vertical inclined or angular ends A' and A², their opposing faces contacting. The inclines or angular ends are formed some distance from the side of the rails, thus forming abutting shoulders a and a', respectively. By this construction the abutting portions will offer longitudinal resistance from impact, or creeping of the rails.

Arranged laterally on the inclines A' and A², are lugs B, projecting from the material forming the tread of the rails which are adapted to enter recesses C formed in the material constituting the tread of the rails on said incline A' and A², thus preventing the rail joint from vertical movement, when securely bolted together. The rails are so constructed that they will match when joined together; the faces of the rails having similar lugs B, and recesses C, as indicated in Fig. 2 of the accompanying drawings.

When assembling the rails A, the joints A' and A², are put together; as indicated in Fig. 1 of the drawing, after which fish plates D, D, are bolted to the rails as indicated in Fig. 5, thus holding the parts securely in place.

By this construction of angular joints, which overlap each other, a more stable, durable and practical joint is obtained, as the stress that comes on the edge of a rail

will not affect the angular joint when secured by fish plates, in combination with the lugs thereon.

I do not limit myself to the exact construction of an angular rail joint, as herein shown and described, as angular joints differing somewhat from this construction may come within the scope of the present invention.

10 That which I consider as new and desire to claim by Letters Patent, is:—

15 1. A rail joint comprising two rails having their opposing ends beveled, and provided with shoulders, a recess formed in the head of one of said rails below the surface thereof near the said shoulder, and a lug formed on the other end thereof, the other rail being provided with a recess in the head

thereof below the surface to receive the lug of the first rail and a lug adapted to enter 20 the recess in the said first rail.

2. In a rail joint, a pair of rail ends each formed with angular contact portions and a shoulder abutting against the other rail end, each rail being also formed with a lug and a 25 recess in the head thereof disposed below the surface of the rail, the lug of one rail being adapted to enter the recess of the other rail end.

In testimony whereof I affix my signature 30 in presence of two witnesses.

ALBERT J. HOLT.
